UNITED STATES PATENT OFFICE

JOHN E. BELL, DECEASED, LATE OF BROOKLYN, NEW YORK, BY LOLA R. BELL, EXECUTRIX, OF BROOKLYN, NEW YORK, ASSIGNOR TO SINCLAIR REFINING COMPANY, OF NEW YORK, N. Y., A CORPORATION OF MAINE

ART OF CRACKING HYDROCARBONS

Application filed January 22, 1925. Serial No. 3,987.

This invention relates to improvements in the production of gasoline, or similar light hydrocarbon oils, by cracking heavier hydrocarbon oils, such as gas oil, by distillation under pressure. The invention includes improvements in the operation of pressure cracking stills, and more particularly in the operation of reflux or fractionating towers employed in conjunction with pressure cracking stills.

When heavy hydrocarbons are distilled under pressure, they are "cracked" with the production of lighter oils. In the commercial operation of a pressure still, some definite product or group of products, for example gasoline or pressure distillate, is usually desired but the vapors escaping from the still itself may include heavier constituents in addition to the constituents desired in the pressure distillate. The vapors from the pressure still are commonly subjected to a refluxing operation before being condensed to effect, to a greater or less extent, the return of such heavier vaporized constituents to the still for further treatment therein, but, as ordinarily practised, such methods have nevertheless resulted in the production of pressure distillates containing large amounts of constituents heavier than the desired pressure distillate. For example, in treating gas oil for the production of gasoline by such cracking methods, the pressure distillate usually includes a considerable amount of constituents of a kerosene character and others even heavier, so that it is necessary to subject a relatively large amount of crude pressure distillate to redistillation to fractionate it into merchantable products and to separate the heavier components.

It is one of the objects of the present invention to eliminate such redistillation of the pressure distillate as a separate operation and to save heat usually employed for such redistillation. Other and further objects will appear more fully as the description proceeds.

According to the present invention, the heat of the pressure distillate vapors escaping from the pressure still is employed to fractionate the pressure distillate in an improved manner, and it may also be employed

in an advantageous way for fractionating at the same time other oils or distillates including constituents suitable as components of the desired product or products.

According to the present invention, the vapors from the pressure still are passed successively through two towers, charging stock to the still is introduced directly into the tower which the vapors first enter and reflux and admixed charging stock from this tower are returned to the pressure still, and an oil or distillate including constituents suitable as components of the desired distillate is introduced directly into the second tower which the vapors escaping from the first enter.

In the first tower, the tower which the vapors first enter, the vapors are contacted with the charging stock introduced therein, the charging stock acting as a refluxing agent and refluxing the heavier constituents of the vapors to the still for further treatment in the still, while the charging stock is at the same time preheated. The first tower thus acts to effect an initial separation of the heavier constituents and return them to the still and also to return to the still for useful application in the cracking operation therein a part of the heat of the escaping vapors. The vapors escaping from the first tower may comprise the normal pressure distillate constituents, that is the components of the desired product associated with some heavier constituents but freed of the heaviest constituents.

In the second tower, the tower which the vapors escaping from the first tower enter, the vapors are contacted with an oil or distillate including constituents suitable as components of the desired distillate which constituents are thereby vaporized. The vapors entering the second tower are partly cooled in the first tower and the vaporization of the lighter constituents of the oil introduced into the second tower further cools them. The heavier constituents of the entering vapors are thus condensed and mix with the unvaporized constituents of the introduced oil, collecting as tower condensate. The vapors escaping from the second tower include the lighter constituents of the vapors entering from the first tower and the light constituents

uents of the introduced oil and may be condensed in the usual way. An accurate fractionation of the vapors from the still, and likewise of the introduced oil, is thus effected by the heat of the pressure distillate vapors, the condensate of the vapors escaping from the second tower comprising the desired pressure distillate substantially free from heavier constituents, and the tower condensate comprising the intermediate constituents heavier than the desired pressure distillate components and lighter than the constituents refluxed to the pressure still from the first tower.

As compared to operations in which it is attempted to reflux directly to the still from a reflux tower thereon (for example the first tower described herein) all constituents heavier than the desired pressure distillate, the process of the present invention accomplishes a marked heat economy. Where heavier constituents having a boiling point close to the temperatures maintained in the pressure still are refluxed to the still they are cracked, with the production of additional amounts of the desired light constituents before they are vaporized in the still; but where intermediate constituents, heavier than desired in the pressure distillate but having a boiling point materially lower than the temperature maintained in the still, are so returned directly to the still charge in substantial amounts an excessive amount of heat is consumed in revaporizing in a cyclic manner these intermediate constituents without cracking with a resulting decrease in the rate of cracking and the capacity of the pressure still.

In carrying out the present invention, the useless consumption of heat in revaporizing such intermediate constituents is avoided while the heat of the vapors is nevertheless employed to advantage in fractionating the vapors for the separation of a pressure distillate of the desired character. The heavier constituents of the vapors, susceptible to further cracking in the pressure still, are refluxed to the pressure still from the first tower, and the intermediate constituents heavier than suitable as components of the desired distillate are separated from the vapors in the second tower. The condensate collecting in the second tower may be subjected to further cracking treatment, for example in a pressure still operated at a higher pressure or in vapor phase cracking apparatus, or it may be disposed of otherwise.

The oil introduced into the second tower may be an oil or distillate independent of the pressure still operation, or it may advantageously be a part of the final pressure distillate produced in the operation as the condensate of the vapors escaping from the second tower. Where an independent oil or distillate is employed it is in effect fractionally distilled in the second tower by the heat of

the vapors, the vaporized constituents escaping with the uncondensed pressure distillate vapors and the heavier unvaporized constituents collecting in admixture with the pressure distillate vapor constituents condensed by the cooling effect of the vaporization.

Where a part of the pressure distillate condensate is introduced, the introduced oil is more or less completely vaporized, only the heaviest constituents, if any, remaining unvaporized, while the cooling effect of the vaporization effects a sharp refluxing of the heavier constituents of the pressure distillate vapors, particularly of the constituents heavier than the vaporized constituents. A close fractionation between constituents suitable as components of the desired pressure distillate and the heavier constituents is thus effected. Where a part of the pressure distillate is so employed, the oil introduced into the second tower contains no substantial amount of constituents heavier than the desired pressure distillate components and no heavier constituents can get into the pressure distillate from that source while the part of the pressure distillate returned is an effective refluxing agent. In this way, by regulating the amount of pressure distillate introduced into the second tower, the character of the pressure distillate as well as of the tower condensate can be closely controlled.

The invention will be further described in connection with the accompanying drawings which show, in a somewhat diagrammatic and conventional manner, an apparatus adapted for the practice of the process of the invention; but it is intended and will be understood that the invention is not limited to the specific methods of operation described in connection with this particular apparatus. The accompanying drawings represent, in elevation and partly in section, a pressure still system adapted for the practice of the process of the invention. The pressure cracking still illustrated in the drawings is of the general construction and operation described and illustrated in United States Letters Patent No. 1,285,200 granted to the Sinclair Refining Company, November 19, 1918 on the application of Edward W. Isom. It will be apparent that the process of the invention may be carried out in connection with pressure cracking stills of other and different types.

The pressure still illustrated comprises the bulk supply tank 1 located away from the heating furnace, the vertically arranged heating tubes 2 located in the heating flue of the furnace, and circulating pipes 3, 4 and 5 connecting successively the bulk supply tank, the circulating pump 6, the lower end of the heating tubes, and the upper end of the heating tubes and the bulk supply tank. A circulating pump may, with advantage, be employed for circulating the oil from the bulk supply

- tank through the heating tubes and back to the bulk supply tank; or the circulating pump may be omitted and thermosiphonic action relied upon for maintaining circulation but with decreased still capacity. 5 Arranged above the bulk supply tank is the reflux tower 7 having a series of baffles therein and connected with the vapor dome of the bulk supply tank through the vapor line 8. 10 The pump 9 is arranged for introducing fresh charging stock into the upper end of the reflux tower through connections 10 and 11; and the return reflux line 12 is arranged for returning reflux and admixed fresh oil from 15 the lower end of the reflux tower to the circulating connection 3 on the suction side of the circulating pump. A connection 13 is also provided for introducing fresh charging stock into the circulating oil through the 20 bearings of the circulating pump. A connection 14 is arranged at the lower part of the circulating connection for pumping out and charging the still, and a tar draw-off connection for use during the operation of the still 25 is provided at 15.
- The second tower 16 is arranged beside the reflux tower 7 and a vapor connection 17 is provided for conducting vapors from the upper end of the reflux tower to the lower end 30 of the second, or fractionating, tower. The vapors escape from the top of the second tower through the vapor line 18 to the condenser 19 which is arranged to discharge into the receiver 20. From the receiver, the 35 condensed pressure distillate is discharged through valved connection 21 and the uncondensed vapors and gases through the valved connection 22. From the receiver, the condensed distillate may be discharged into the 40 pressure distillate tank 23, or through connection 24. The pump 25 is arranged for introducing a refluxing agent into the upper end of the fractionating tower through connection 26. The refluxing agent so supplied may 45 be pressure distillate withdrawn from the tank 23 withdrawn through connection 27 or it may be supplied through a separate source from connection 28. A connection 30 is arranged for discharging the condensate mixture produced in the fractionating tower 50 16 from the lower end of the fractionating tower.
- The pressure may be regulated and reduced 55 by means of a regulating valve 29 interposed between the fractionating tower and the condenser, or the still pressure may be maintained through the condenser and the pressure regulated and controlled by a suitable 60 valve or valves arranged beyond the condenser.
- In carrying out the process of the invention 65 in the apparatus illustrated, the pressure still is charged and brought to the cracking conditions of temperature and pressure in
- the usual way. As cracked vapors escape from the still additional charging stock is introduced through the reflux tower 7 and the charging stock and admixed refluxed constituents are returned to the still from the reflux tower. Tar may be withdrawn as the 70 operation proceeds, and the rate of tar withdrawal and the rate of supply of fresh charging stock may advantageously be regulated to maintain the concentration of pitch constituents in the charge below saturation. The 75 vapors escaping from the reflux tower 7 enter the fractionating tower 16 where they are directly contacted with an oil refluxing agent introduced through connection 26. The supply of refluxing agent is regulated to control the character of the vapors escaping from the fractionating tower and to condense in the fractionating tower the vapor constituents heavier than those suitable as 80 components of the desired pressure distillate. The condensed constituents of the vapors and the unvaporized constituents of the refluxing agent are withdrawn through connection 30. The vapors escaping from the fractionating 85 tower are condensed in the condenser 19 and the condensate collected as the desired pressure distillate. 90
- In cracking gas oil for the production of gasoline, for example, the still is initially 95 charged with gas oil and additional gas oil charging stock is introduced through the reflux tower as the operation proceeds. The reflux returned to the still from the reflux tower includes any gas oil character constituents of the vapors and may also include heavier kerosene character constituents but is substantially free of gasoline constituents. The vapors, including the gasoline constituents, escape to the fractionating tower and a 100 refluxing agent including gasoline constituents is introduced into direct contact with the vapors in the fractionating tower. The gasoline constituents of the refluxing agent introduced into the fractionating tower are 105 vaporized by the heat of the vapors from the reflux tower and the vaporization of these constituents cools the vapors in the fractionating tower. The supply of refluxing agent is regulated to absorb sufficient heat, in vaporization of the lighter constituents thereof, to condense the vapor constituents heavier than gasoline without condensing the gasoline components. The heavier constituents are 110 thus condensed in the fractionating tower, and the gasoline constituents of the cracked vapors together with the gasoline constituents of the refluxing agent escape and are 115 condensed as the desired pressure distillate. A gasoline character pressure distillate is thus 120 produced directly.
- For the production of gasoline, the refluxing agent may, for example, be a part of the pressure distillate, or a naphtha character fraction including gasoline constituents and 130

heavier components such as kerosene constituents, or a gasoline fraction such as a straight run gasoline to be blended with the pressure distillate may be employed as the refluxing agent. Very close fractionation can be obtained by employing a part of the pressure distillate itself, the reintroduced pressure distillate being substantially completely re-vaporized in the fractionating tower, the heat absorbed by the vaporization being available therein to effect the desired fractional condensation. Where a naphtha character fraction is used, such as a crude pressure distillate as ordinarily produced in running for gasoline containing upwards of about 50% gasoline the naphtha is also fractionated in the fractionating tower, the heavier constituents of the naphtha collecting with the condensate in the tower and the gasoline constituents escaping with the gasoline constituents of the pressure still vapors. The operation of a pressure still in accordance with the present invention may thus be combined with advantage with other pressure still operations carried out in the usual manner, and the crude pressure distillate from one or more other pressure stills fractionated, or redistilled, in conjunction with the pressure still operation of the present invention. The amount of crude pressure distillate which can be so fractionated will depend upon the relative proportion of gasoline constituents in the crude pressure distillate as well as upon the concentration of gasoline constituents in the vapors entering the fractionating tower. A blending operation may also be advantageously combined with the process of the present invention and the gasoline, or gasoline fraction, for blending at the same time utilized for fractionating the pressure distillate vapors. In such a combined blending operation, any heavier constituents of the gasoline for blending may also be eliminated from the composite pressure distillate.

It will thus be seen that the present invention enables the direct production of a pressure distillate substantially free from constituents heavier than those suitable as components of the desired pressure distillate. The elimination of such heavier constituents from the pressure distillate, or the increased concentration of the desired constituents in the pressure distillate, reduces the cost of refining the pressure distillate. Redistillation may be avoided. The amount of pressure distillate that must be handled for each gallon of the desired product is also reduced. This in turn reduces the amount of equipment, labor and chemicals required for subsequent chemical treatment, and also reduces the amount of equipment, labor and fuel required if the pressure distillate is redistilled. The improved fractionation effected also substantially eliminates from the pressure distillate any entrained heavier constituents of the

charging stock introduced into the first tower on the still such as might carry with them objectionable impurities or otherwise interfere with subsequent refining operations. The improved fractionation effected may also actually increase the amount of the desired pressure distillate produced. The refluxing operation carried out in the first tower may be regulated so that substantially none of the desired pressure distillate constituents are refluxed to the still therein, where they might be subjected to overcracking, while the fractionating operation carried out in the second tower, from which condensed constituents are not returned to the still, may be controlled to eliminate from the pressure distillate vapors escaping from the second tower substantially all constituents heavier than desired as components of the pressure distillate. The cooling of the pressure distillate vapors in the second tower also assists in reducing the amount of cooling water employed for condensing the pressure distillate.

Another important advantage of the present invention is that it does not require the use of bubble towers or other fractionating towers in which the flow of vapors is materially restricted. One of the disadvantages of such fractionating towers when employed in conjunction with pressure stills is the possibility of development of excessive pressures because of the restriction of vapor flow and, moreover, if the conditions in the tower are disturbed a more or less prolonged period is required to bring the tower back to normal operation. In carrying out the present invention, on the other hand, the second tower may be of ordinary baffle construction providing a relatively large area for the free flow of the vapors. The path through such a tower is also relatively short and the heat exchanging relations in the tower are comparatively simple and subject to direct and immediate control. An easily controlled and simple operation is thus provided while at the same time the direct introduction of part of the pressure distillate or of an oil containing constituent suitable as components of the pressure distillate enables close fraction of the pressure distillate and the substantial elimination of heavier constituents therefrom. Where an ordinary baffle tower is so employed, a wide range of products can also be produced without changing the design of the tower regulating the amount and character of the refluxing medium introduced into the tower.

It will also be seen that the present invention provides an improved method of fractionating pressure distillate, which in effect may be considered a redistillation of the pressure distillate in which the heat of the pressure distillate vapors is employed in a particularly advantageous way for carrying out the redistillation. In the direct produc-

tion of gasoline, for example, as a pressure distillate product, the present invention provides an improved process which is easily controlled and which can be carried out in conjunction with the pressure still operation without interfering therewith while at the same time usefully employing heat usually wasted in heating the cooling water employed to condense the pressure distillate. In the combined operation of the present invention, moreover, the pressure distillation itself may be improved, heavier constituents of the vapors escaping from the pressure still susceptible to further cracking treatment therein being refluxed to the still and part of the heat of the vapors being returned to the pressure still in the fresh charging stock for further application to the cracking operation therein, and intermediate constituents which might cause an excessive consumption of heat in revaporization without useful cracking if returned directly to the still charge being separated from the pressure distillate vapors without being returned to the pressure still.

What is claimed as new and desired to be secured by Letters Patent of the United States is:

1. An improved method of cracking gas oil for the production of gasoline, which comprises heating a body of gas oil at the cracking temperature by circulating oil from the body through heating tubes and back to the body and distilling off vapors generated thereby under pressure, subjecting the vapors from the distilling operation to a refluxing operation in direct contact with fresh gas oil charging stock, returning the reflux and admixed gas oil constituents to the distilling operation, subjecting the vapors from the refluxing operation to a fractionating operation in direct contact with an oil containing gasoline constituents, withdrawing an intermediate condensate including kerosene constituents from the fractionating operation whereby the boiling range of the condensates returned to the distilling operation is restricted, withdrawing the gasoline constituents from the fractionating operation as vapors and condensing them, and supplying part of the condensate so produced to the fractionating operation as the oil containing gasoline constituents.

2. An improved method of cracking heavier hydrocarbon oils for the production of lighter hydrocarbon oils, which comprises heating a body of the heavier oil at the cracking temperature by circulating oil from the body through heating tubes and back to the body and distilling off vapors generated thereby under pressure, subjecting the vapors from the distilling operation to a refluxing operation, returning the reflux to the distilling operation, subjecting the vapors from the refluxing operation to a fractionating oper-

ation in direct contact with an oil including constituents suitable as components of the desired pressure distillate, withdrawing an intermediate condensate including kerosene constituents from the fractionating operation whereby the boiling range of the condensates returned to the distilling operation is restricted, condensing the vapors escaping from the fractionating operation, and supplying part of the condensate so produced to the fractionating operation as the oil including pressure distillate constituents.

In testimony whereof I affix my signature.
